UNITED STATES PATENT OFFICE

JAMES S. GEORGE, OF WATERBURY, CONNECTICUT, ASSIGNOR TO SCOVILL MANUFACTURING COMPANY, OF WATERBURY, CONNECTICUT, A CORPORATION OF CONNECTICUT

STREET MARKER

Application filed May 7, 1929. Serial No. 361,027.

This invention relates to improvements in street markers, that is, devices now widely used arranged to be embedded in the street or other place to provide directions for the proper control of traffic or for other purposes.

In certain types of these markers, the marker consists of a head provided with legs and with devices for expanding or spreading the legs into engagement with the pavement. 5 a hole being first made in the pavement for the reception of the shank. With devices of this type, it frequently happens that the holes are carelessly bored and are of an improper depth, so that when it is attempted to set the 10 marker in position, there is no bottom for the spreading device to act against, with the result that engagement of the holding legs with the pavement is not accomplished. This 15 is particularly disadvantageous where the marker is to form part of a design, and it is necessary to bore another hole, thus throwing that marker out of place.

The especial object of the present invention is to provide a marker having holding 25 legs together with a spreading device which will act to spread the legs into engagement with the pavement regardless of the depth of the hole which has been bored to receive the shank and legs of the marker.

30 A further object of the invention is to provide a spreader construction which will act to lock the parts in position, so that the legs cannot spring back after they have once been set and thus loosen the marker.

35 With these and other objects not specifically referred to, the invention consists in certain novel parts, arrangements and combinations which will be described in connection with the accompanying drawings and 40 the novel features pointed out in the claim hereunto appended.

Referring to these drawings—

45 Figure 1 is a plan view of the improved marking device;

50 Figure 2 is a sectional view showing the marker in position in the pavement, with the parts not set; and

55 Figure 3 is a sectional view similar to Fig. 2, showing the parts of the marker in set 60 position.

Referring to said drawings, the pavement is indicated by the letter P, and in the pavement is formed, as by boring, a hole H, this hole being designed to receive the locking parts of the marker.

65 The marker itself is made of metal and comprises a head 2, the top of which is preferably rounded, as at 3, so that there is no obstruction to anything passing over it. The under face of this head is flat, or substantially flat, as indicated at 4, so as to lie flat against the pavement. This head has associated therewith a shank 5 which is divided, as by slitting the metal, into spaced holding fingers 6. The number of these fingers may, 70 of course, be varied, but in the particular construction illustrated, there are four of these. The outer faces of these fingers are plain, as indicated in the drawings, and the inner faces are formed with inwardly and 75 downwardly extending cam faces 7 which terminate in a sharp edge 8, the faces of the leg below the edge 8 facing downwardly and outwardly, as indicated at 9, forming in effect a shoulder. The head is provided with 80 an opening or aperture 10, and the shank is formed with a recess 11. Cooperating with this head and shank is an improved spreading device shown in the form of a metal rod 12 which may be of the same metal 85 or a different metal from that of which the head is composed. This rod 12 at its lower end is provided with a coned end 13 above which is a shallow groove 14 forming a shoulder 15. The coned end is of greater 90 diameter than the opening between the inner edges 8 of the legs 6, so that when the rod is driven into position by the application of pressure to the upper end thereof, the coned end acts to spread the legs 6 from the position shown in Fig. 2 to that shown in Fig. 95 3, and this causes the legs to engage the pavement at the sides of the hole.

100 It will be observed that it is unnecessary for the hole to be the exact depth of the legs, and that the spreader rod will exercise its function irrespective of the depth of the hole. It will further be observed that after the coned end of the spreader rod passes the edges 8, these will engage the shoulder 15.

formed by the groove 14 and the legs are locked in spread position, so that danger of the legs springing back and thus loosening the marker is eliminated.

5 While the invention has been shown and described in its preferred form, it will be understood that certain variations in the shape and arrangement of the parts may be made without departing from the invention,
10 as defined in the claim hereto annexed.

What is claimed is:

A street marker comprising a head of sufficient size to be readily visible at considerable distances, said head having an aperture and a relatively large flat under face, a relatively slender shank depending from said head for entering a hole in a pavement, said shank having holding fingers arranged in a generally circular manner and a recess 20 in line with the aperture in the head, said fingers having inner faces with inwardly and downwardly extending cam faces terminating in sharp lower edges and shoulders below said edges, and a rod having a coned portion and a shoulder above said coned portion, said rod being adapted to be driven into said aperture and recess and the coned portion to exert a sliding wedging action on the cam faces whereby the fingers are forced 25 outwardly in a radiating fashion into engagement with the pavement and the flat face drawn against the pavement surface, the shoulder on the rod lockingly engaging the shoulders of said fingers after the rod 30 has been driven in.

In testimony whereof, I have hereunto set my hand.

JAMES S. GEORGE.

CERTIFICATE OF CORRECTION.

Patent No. 1,776,660.

Granted September 23, 1930, to

JAMES S. GEORGE.

It is hereby certified that error appears in the printed specification of the above numbered patent requiring correction as follows: Page 2, line 15, in the claim, before the word "flat" insert the word substantially; and that the said Letters Patent should be read with this correction therein that the same may conform to the record of the case in the Patent Office.

Signed and sealed this 21st day of October, A. D. 1930.

**M. J. Moore,
Acting Commissioner of Patents.**
